(57) **CLAIM**

The ornamental design for a lighting fixture, as shown and described.

DESCRIPTION

FIG. 1 is a front right perspective view from above of a lighting fixture according to the new design;

FIG. 2 is a front left perspective view from below thereof;

FIG. 3 is a rear left perspective view from above thereof;

FIG. 4 is a front elevational view thereof;

FIG. 5 is a right side elevational view thereof;

FIG. 6 is a left side elevational view thereof;

FIG. 7 is a rear elevational view thereof;

FIG. 8 is a top view thereof;

FIG. 9 is a bottom view thereof;

FIG. 10 is a front right perspective view from above of an alternative embodiment of the lighting fixture having translucent surfaces according to the new design;

FIG. 11 is a front left perspective view from below thereof;

FIG. 12 is a rear left perspective view from above thereof;

FIG. 13 is a front elevational view thereof;

FIG. 14 is a right side elevational view thereof;

FIG. 15 is a left side elevational view thereof;

FIG. 16 is a rear elevational view thereof;

FIG. 17 is a top view thereof;

FIG. 18 is a bottom view thereof;

FIG. 19 is a front elevation view of an alternate embodiment of the lighting fixture seen in FIGS. 1-9, the only difference being the symbolic break lines in the lighting fixture, it being understood that all other appearances are the same as FIGS. 1-9; and,

FIG. 20 is a front elevation view of an alternate embodiment of the lighting fixture seen in FIGS. 10-18, the only difference being the symbolic break lines in the lighting fixture, it being understood that all other appearances are the same as FIGS. 10-18.

The broken lines in the drawings illustrate portions of the lighting fixture that form no part of the claimed design.

The stippling shown in the drawings represents a contrast in appearance. FIGS. 19 and 20 show the lighting fixture with symbolic break lines in its length and width. The appearance of any portion of the article between the break lines forms no part of the claimed design.
